DESIGN FOR A SHELF FOR LAUNDRY TUBS

Rudolph J. Steiner, St. Paul, Minn.

Application November 28, 1940, Serial No. 96,910

Term of patent 14 years

To all whom it may concern:

Be it known that I, Rudolph J. Steiner, a citizen of the United States, residing at St. Paul, in the county of Ramsey and State of Minnesota, have invented a new, original, and ornamental Design for a Shelf for Laundry Tubs, of which the following is a specification, reference being had to the accompanying drawing, forming a part thereof.

In the drawing:

Fig. 1 is a top perspective view of a shelf for laundry tubs showing my new design;

Fig. 2 is a bottom perspective view thereof; and
Fig. 3 is an end elevational view thereof.

I claim:

The ornamental design for a shelf for laundry tubs, as shown.

RUDOLPH J. STEINER.
